UNITED STATES PATENT OFFICE.

ARTHUR F. POOLE, OF KENILWORTH, ILLINOIS, ASSIGNOR TO WAHL COMPANY, OF WILMINGTON, DELAWARE, A CORPORATION OF DELAWARE.

CALCULATING-MACHINE.

1,314,094.

Specification of Letters Patent. Patented Aug. 26, 1919.

Application filed May 9, 1917. Serial No. 167,464.

To all whom it may concern:

Be it known that I, ARTHUR F. POOLE, a citizen of the United States, residing at Kenilworth, in the county of Cook and State 5 of Illinois, have invented certain new and useful Improvements in Calculating-Machines, of which the following is a specification.

My invention is an improvement in calculating machines, particularly in that class in which there is an escapement controlled decimal carriage and an auxiliary rack on the carriage, into which rack some of the calculating parts are locked during the actuation thereof, for the purpose of preventing accidental displacement of the decimal carriage during the period of calculation. The specific embodiment of my invention which I have herein shown is in the well-known Wahl typewriter adding and subtracting machine, said machine being described in numerous patents, particularly in the patent to J. C. Wahl, No. 893,719 of July 21, 1908. In the Wahl machine there 20 is a calculating attachment which is attached to a Remington typewriter and is operated by the numeral keys thereof. The calculating attachment is of the well-known ten key type, that is, there is present a decimal carriage and ten numeral keys, any one of which may coöperate with a totalizer in any one of the decimal places of said totalizer. The totalizer is mounted on a traveling truck, whose motion is controlled by the carriage of the typewriter, which in its turn is controlled by the usual typewriter escapement. In order to insert a number in this Wahl machine, the typewriter carriage is first tabulated to the highest decimal place 25 of the number and then the numeral keys are depressed in order according to the digits of said number and after each key is depressed the typewriter carriage escapes one space, carrying the decimal carriage with it, and thus the number is inserted into the totalizer digit by digit.

In the Wahl machine, in order to prevent misoperation thereof, it is customary to provide the truck on which the totalizer is 30 mounted with a locking rack and to lock parts of the calculating attachment into said rack during the actuation of any of the numeral keys. This is for the purpose of preventing accidental displacement of the type-

writer carriage and its connected truck during the insertion of a number into the totalizer. In the Wahl machine the escapement rack which controls the escapement of the carriage is usually located in the rear part of the carriage and the truck carrying the totalizer and the locking rack just referred to is located on the front side of said carriage. The members which coöperate with these racks are, of course, rotatably mounted on the framework of the typewriter. In consequence of this arrangement there is present the condition of having the typewriter carriage located by the escapement rack at the rear of the carriage and also having the carriage located by the locking rack at the front of the carriage. This condition necessitates very accurate workmanship, both in the spacing of the escapement rack at the rear of the carriage and in the spacing of the locking rack at the front 70 of the carriage. Furthermore, this construction necessitates very accurate workmanship in the maintaining of the typewriter carriage bearings in proper condition so that these bearings will permit of no 75 lost motion between the carriage and the typewriter framework.

It is necessary, from consideration of wear, to make the escapement rack of somewhat heavy metal and to make this rack 80 hard. It is well known that when a piece of steel of the size of an escapement rack is hardened that there is a certain amount of distortion, due to the unequal expansion of the metal during the hardening process, 85 and it is therefore very difficult to make the escapement rack and the locking rack both hard and at the same time maintain an exact spacing of the teeth of these racks. Even if the racks are made absolutely accurate when soft, they will distort enough during hardening to have, in extreme cases, as great a difference as from five to ten thousandths of an inch between the position of 90 corresponding teeth on the two racks. Practically the only way to get these racks in absolute registration is to take one of them, preferably the escapement rack, as a standard and grind the teeth of the locking rack to match the teeth of the escapement rack. 95

In practice the cost of adjusting these two racks to each other is so great as to be commercially prohibitive and, as usual in such

cases, a compromise is adopted; that is, the teeth of the escapement rack are made hard and the teeth of the locking rack are left soft, and by operating the machine for a time before it is put on the market, the soft teeth of the locking rack become worn into correspondence with the hard teeth of the escapement rack. However, this process is somewhat unsatisfactory and especially so from the consideration that if either the locking rack or the escapement rack should become damaged it is necessary to provide two new racks instead of one. Another commercial disadvantage of this practice is that the locking rack being necessarily soft, does not wear as long as it would if it were possible to harden said rack and thus the effective life of the machine is materially lessened.

Another difficulty which arises from the fact of the escapement rack and the locking rack not being in exact correspondence is that in case the locking rack as a whole is slightly out of its correct adjustment in respect to the typewriter rack then, when the numeral key is depressed consequently throwing a locking member into this locking rack, the whole typewriter carriage is moved bodily a short distance, thereby throwing an undue load upon the numeral key and making the action of the machine harder than would be the case if the escapement rack and locking rack were in perfect adjustment.

It is the object of my invention to provide a structure for calculating machines of the type of the Wahl machine, (which throughout this specification I shall take as a typical example, although my invention is by no means confined to use with the Wahl machine) which will allow the use of an escapement rack and a locking rack which are not in perfect correspondence or adjustment, and, as a result, of allowing the use of these practically inaccurate racks, permitting both of the racks to be made hard, thereby insuring greater wear and also to entirely avoid the necessity of replacing two racks in case one of them should be damaged or of wearing one of the racks into correspondence with the other, as hereinbefore described.

A further object of my invention is to greatly cheapen the construction of machines of this character and to minimize the undesirable results of either the escapement rack or the locking rack coming slightly out of adjustment during the operation and use of the machine after it has left the manufacturer. These and other objects of my invention will be apparent to those skilled in the art from the following specification and claims.

My invention may be best understood by

reference to the accompanying drawings, in 65 which—

Figure 1 is a sectional view of some of the calculating parts of a Wahl machine;

Fig. 2 is a detail view of a certain floating locking member and master wheel employed 70 therein;

Fig. 3 is a detail view, partly in section, taken along the line 3—3 of Fig. 1;

Fig. 4 is a side elevation of a typewriter upon which my invention is mounted, and 75

Fig. 5 is a diagrammatic top view of a typewriting adding machine embodying my herein described invention.

Similar figures of reference serve to identify like parts in all the views.

As before noted, while I have described the preferred embodiment of my invention on a Wahl machine, yet this machine is only taken because it is in a manner typical of one class of machines to which my invention 85 may be advantageously applied.

Referring to Figs. 1 and 4, I have shown a typewriter 10, on which is mounted the usual carriage 11, serving to support the platen 12. On the carriage is mounted the usual escapement rack 13, in mesh with which is a spur gear 14, rotatably mounted in a bearing 15 on the framework of the machine. Attached to the spur gear 14 and rotating therewith are the usual Remington 95 escapement wheels 17 and 18, which are engaged by a dog 19, rocking on a pivot 20 in the framework of the machine and having rigid therewith a crank 21, which is connected by a pull rod 22 to an arm 23, mounted on a rocker 24, and having an arm 25 rigid therewith. A universal bail 26 extends under all of the typewriter keys, including numeral keys 27, and is supported from the arm 25 by a link 28. A similar 100 arm 25 and supporting link 28 (not shown) serves to support the bail 26 at the other side of the typewriter and thus it will be readily seen that depression of any of the numeral keys 27 will, by reason of the chain 105 of mechanism just described, result in the rocking of the escapement dog 19. The typewriter carriage 11 is urged to the left by the customary tape and spring (not shown) and as a result thereof will be advanced step by step upon operation of the 110 keys 27.

The usual step advance of the typewriter carriage is one-tenth of an inch. For ordinary typewriter work this need be only 115 approximately correct. It may vary one to two per cent. either way without being noticed. Obviously the exact location of the typewriter carriage depends on (1) the accuracy of the rack 13, (2) the accuracy of the gear 14 and (3) the accuracy of the gears 17 and 18. Errors in any of these particulars or in all of them may all operate in 120 125

the same direction, or may operate to offset each other. However, it will be readily apparent that the maintenance of an exact spacing of one-tenth of an inch in the step-by-step motion of a typewriter carriage is a matter of quite a good deal of mechanical difficulty.

Considering now the calculating portion of a machine, there is a totalizer 29, which is mounted on a truck 30, which is connected at either end to the typewriter carriage by brackets 31, 32. This truck is supported in a casting 33, attached to the front portion of the framework of the typewriter. In this casting are mounted rollers 34, 35, which serve to maintain the truck 30 in its proper position. This construction of the truck and its mounting is described in great detail in the patent to Webster, No. 968,103, dated 20 August 23, 1910, and therefore need not be described here. Mounted on the truck 30 is the locking rack 36, whose functions will hereinafter be described.

The truck 30, as before noted, serves as a support for the totalizer 29. The parts of this totalizer are shown in detail in the sectional view of Fig. 1, and since these parts are described in several issued patents, particularly the one to Wahl *supra*, it will not be necessary to describe these parts here, except to note that there is present in the totalizer a series of carrying wheels 37, which are rotatably mounted on a shaft 38, and are acted on in succession by a master wheel 39, mounted on a rotatable shaft 40.

The numeral keys 27 of the typewriter 10 are connected by pull rods 41 to certain mechanism in the actuator thoroughly described in the cited Wahl patent. Depression of any typewriter numeral key 27 results in the rotation of the master wheel 39 a differential amount and the rocking of a master dog 42, which is pivoted on a shaft 43 in the framework of the actuator. The cycle of operations of these two parts, that is, the master wheel 39 and the dog 42, is as follows: Upon the first part of the depression of the typewriter key 37 the master dog 42 is rocked on its shaft 43 in a counterclockwise direction (Fig. 1). The dog performs certain operations in the totalizer which need not be herein specified, and after this rocking of the dog has taken place the master wheel 39 is rotated a differential amount, depending upon the particular numeral key 27, which has been operated. Before the key has completed its down stroke and after the completion of the differential rotation of the master wheel 39, the master dog 42 is released and returns to its original position. The typewriter carriage then escapes and the master wheel 39 comes into mesh with the totalizer gear 37 of next lower denomination.

Rigid with the master dog 42 and therefore also rocking on the shaft 43 is a locking dog 44, which is adapted to engage in the teeth of the locking rack 36. Since it will be remembered that the master dog 42 is held in its displaced position during the differential rotation of the master wheel 39, it is evident that the truck 30 and its thereon mounted totalizer 29 will be held immovable as far as the framework of a typewriter is concerned during the differential rotation of the master wheel.

I have explained the foregoing mechanisms in only a somewhat general way, since they are well known in the Wahl adding machine and have been described in numerous patents to Wahl and others.

I shall now describe the mechanism which is peculiar to my invention:

Referring particularly to Fig. 2, it will be seen that the master dog 42 is mounted on a shaft 43 and that this shaft in its turn is mounted in two plates 45 and 46, which are rigid to the framework of the machine. The shaft 43 is made to have considerable end play or lateral motion between the plates 45 and 46, since it will be noted in Fig. 2 that the length of the shaft 43 between its shoulders is somewhat less than the distance between said plates. The locking dog 44 is rigid with the master dog 42, and also with a fork 47, the prongs of which embrace the master wheel 39. The master wheel is rigidly mounted on a shaft 48, which turns between the side plate 45 and a plate 49, also rigid to the framework, and it will be observed that, as in the case of the shaft 43, the distance between the shoulders of the shaft 48 is somewhat less than the distance between the two plates in which said shaft has a bearing. In practice, I have found that giving these shafts a lateral motion of twenty-thousandths of an inch is sufficient and will take care of the greatest discrepancy which I have found between any two racks.

Slidably mounted on the shaft 48 is the direct gear 50, which has rigid with it a tongue 51, engaging in a fork 52, rigid to the master wheel 39. Meshing with the direct gear is the reverse gear 53, which is rotatably but non-slidably mounted on a reversing shaft 54 and is connected to the direct gear 50 by means of a rocker 55, which has on one end a pin 56, engaging in a slot 57 in the shaft 54, and on the other end a pin 58 engaging in an annular slot 59 in the direct gear 50. The rocker 55 itself is pivoted to the framework on the stud screw 60. Shifting of the reverse shaft 54 will reverse the direction of rotation of the master wheel 39 consequent upon the depression of any of the numerals. It is by this means that the machine may be made to either add or subtract, or when the

reverse shift 54 is placed in an intermediate position, be made not to calculate. However, this reversing mechanism has nothing to do with my present invention and has been 5 thoroughly described in several issued patents, in particular my Patent No. 1,198,050, issued September 12, 1916.

The locking dog 44 is provided with a beveled end 61, and the teeth of the locking 10 rack 36 are beveled as shown at 62.

The operation of my improved machine is as follows: The typewriter carriage 11 is located by the escapement dog 19 into some 15 position and since the truck 30 is connected to the typewriter carriage 11 by the brackets 31 and 32, this truck is located in a definite 20 position also. This position may or may not coincide with the locking dog 44, being exactly under the space between two consecutive 25 teeth of the locking rack 36. However, when a numeral key 27 is depressed, the beveled end 61 of the locking dog 44 will contact with the beveled end of the teeth 62 and since the shaft 43 has motion 30 between its side plates, the locking dog 44 will locate itself in a position between the teeth 62 of the locking rack 36. The locating 35 of the locking dog 44 will also result in the locating of the two actuator members 40 which contact with the totalizer, that is, the master wheel 39, since this wheel will be located by the fork 37, and the master dog 42, which will be located by the fact of its being rigid with the locking dog 44. The 45 totalizer itself is, of course, located on the truck by contact of the latch 63 with a locating rack 64 on the upper side of the truck. And the amount of variation between the locating 50 rack and the locking rack 42 will never be great enough to produce an interference between the master wheel 39 and the totalizer wheels 38 on either side of the wheel 38 with which the master wheel is at that time in mesh. The same will be true of 55 the master dog 42, so that when one of the numeral keys 27 is depressed all of the operating parts, viz., the locking dog 44, the master dog 42, the master wheel 39 and the totalizer 29 are locked to the truck 30 and even though said truck be slightly shifted in either direction (such shifting being permitted by the lateral shifting of the shafts 43 and 38) yet the operative connections between the master dog 42, the master wheel 59 and the totalizers, will not be changed and therefore no interference will result.

It is thus evident that by the simple expedient of providing the locking dog so that it will locate itself into the truck, instead of 60 having the locking dog not laterally shiftable in the framework and locating the truck (as has been the construction heretofore) avoids the necessity of any exact correspondence between the escapement rack 14

and the locking rack 36. The operation of 65 my mechanism may be generally described by saying that the typewriter carriage and the truck 30 are first located in a position dependent entirely upon the action of the typewriter escapement. Then when the numeral key of the typewriter is first operated, the calculating parts locate themselves into a position depending upon the position of the typewriter carriage 11. By reason of 70 the simple expedient herein described, it is 75 not necessary to have the racks 36 and 14 in exact correspondence and there is an allowable variation of twenty thousandths of an inch, that is, ten thousandths on either side of the normal position. This standard 80 of accuracy can be easily and cheaply maintained in commercial machines.

I have also, by my herein described invention, obviated the fault which will arise even with perfect racks 36 and 14 of having 85 the entire typewriter carriage shifted bodily by the numeral keys in case the truck 30 becomes slightly out of adjustment. The parts which are located by the coöperation of the locking dog 44 with the locking rack 90 36 are only the two shafts 43 and 48 and these shafts are very light, indeed of practically negligible weight in comparison with the weight of the typewriter carriage itself.

Many modifications and variations may be 95 made from the precise structure herein shown without departing from the spirit of my invention. As before noted, I have described as the preferred embodiment of my invention in its application to the well-known Wahl adding machine. However, this particular machine is taken simply as 100 a type. There are quite a number of calculating machines on the market and which have been proposed in which my herein described invention would be of great advantage. I believe I am the first to show a decimal carriage carrying calculating instrumentalities and controlled by an escapement and providing means to locate other calculating devices in accordance with the position of said carriage before these devices 105 perform their function upon the instrumentalities mounted on the carriage and I wish to claim the same broadly.

Having thus described my invention, I claim:

1. In a calculating machine, the combination of a moving carriage, means to locate said carriage in a series of predetermined 110 positions, calculating instrumentalities carried by said carriage, other calculating devices floating in the framework adapted to coöperate with said instrumentalities, and means to locate said devices in a position 115 predetermined by said decimal carriage before said calculating operation is initiated.

2. In a calculating machine, the combina-

- tion of a decimal carriage, an escapement for said carriage, a set of keys operative on said escapement, and means to lock said carriage in position during the depression of 5 any of said keys, said locking means floating in the framework to allow for inaccuracies in said escapement rack. 65
3. In a calculating machine, the combination of a decimal carriage, a set of numeral 10 keys, an escapement for said carriage controlled by said keys, a rack forming part of said escapement, a totalizer, a master wheel to insert numbers therein, a locking device adapted to lock said decimal carriage during the insertion of numbers by said master 15 wheel, said locking device being adapted to float in the framework, whereby the effect of inaccuracies in said escapement rack may be avoided. 70
4. In a calculating machine, the combination of a decimal carriage, a set of numeral 20 keys and an escapement for said decimal carriage including a rack, said escapement being operated upon depression of any of 25 said numeral keys, a totalizer, means to insert numbers therein, the relation of said totalizer and number-inserting means being controlled by said decimal carriage, and locking means to lock said decimal carriage during the insertion of a number, said locking 30 means and number-inserting means being so arranged as to float in their bearings and thereby permit inaccuracies in said escapement rack and still maintain the proper 35 relation between said totalizer and said number-inserting mechanism. 75
5. In a calculating machine, the combination of a decimal carriage, a set of keys, an escapement for said carriage controlled 40 by said keys, said escapement including a rack as one of its parts, a second rack attached to said carriage, means adapted to lock said carriage to the framework of the machine during the operation of any of said 45 numeral keys, said locking means engaging said second rack and said locking means being provided with a floating bearing whereby it may adjust itself to any discrepancies between the two racks. 80
6. In a calculating machine, the combination of a decimal carriage, a set of numeral 50 keys, escapement mechanism including a rack, said mechanism being operated by any of said numeral keys, a locking rack attached to said carriage, a dog adapted to engage the teeth of said locking rack thereby rendering the carriage immovable during the operation of any of said numeral 55 keys, and a floating bearing for said dog in the framework of the machine whereby said dog may accommodate itself to a lack of correspondence between said racks. 85
7. In a calculating machine, the combination of a decimal carriage, a set of numeral 60 keys, an escapement for said carriage adapted to be actuated by said numeral keys, said escapement mechanism including a rack as one of its parts, a second rack attached to said carriage, a locking dog adapted to be actuated by any of said numeral keys to engage said locking rack and thereby lock the decimal carriage during the actuation of any of the numeral keys, and a shaft mounted in the framework of a machine and upon which said dog is mounted, said shaft being 70 provided with lost motion in its bearings whereby the locking dog may accommodate itself to a lack of correspondence between the two racks. 90
8. In a calculating machine, the combination of a decimal carriage, escapement mechanism for said carriage including a rack, a set of keys, means to operate said escapement mechanism consequent upon the actuation of any of said keys, a locking rack 85 also mounted on said decimal carriage, a totalizer, number-inserting means therefor controlled by said keys, said totalizer and number-inserting means having their relative position determined by said decimal 90 carriage, a locking dog adapted to enter the teeth of said locking rack upon the actuation of any of said numeral keys and lock said decimal carriage, a floating bearing for said locking dog, and connections between 95 said locking dog and said number-inserting means whereby the number inserting means will take a position determined by the engagement of said locking dog with said locking rack. 100
9. In a typewriter computing machine, the combination of a typewriter carriage, a set of keys, an escapement mechanism governing the position of said typewriter carriage, said escapement mechanism including 105 a rack and being controlled by any of said keys, a locking rack, means to move said locking rack in synchronism with the motion of said typewriter carriage, and a locking dog slidably mounted in the framework 110 of the machine and adapted to engage said locking rack upon the actuation of any of said numeral keys. 115
10. In a typewriter calculating machine, the combination of a set of keys, a typewriter carriage, escapement mechanism therefor including a rack, said escapement mechanism being adapted to be operated upon the operation of any of said keys and thereby advance said carriage step by step, 120 a locking rack upon said carriage, a dog adapted to engage the teeth of said locking rack, connections between said key and said dog to actuate the same to engage the locking rack upon the actuation of any of said 125 numeral keys, and a shaft for said dog, said shaft being rotatably mounted in the framework and having slight lateral motion there-

to whereby the position of said dog will adjust itself to a lack of correspondence between the escapement and locking racks.

11. In a typewriter calculating machine, 5 the combination of a typewriter carriage, a set of keys, an escapement mechanism controlled by any of said keys and including an escapement rack, a locking rack moving synchronously with said carriage, a totalizer, number-inserting means for said totalizer, a locking dog adapted to enter the teeth of the locking rack and thereby prevent relative motion between the totalizer and its number-inserting mechanism during 10 the insertion of a number, said number-inserting mechanism and said locking dog having a slight lateral motion with respect to the framework of the machine whereby the typewriter carriage is located in respect 15 to the framework during the insertion of a number, and the number-inserting mechanism and locking dog may adjust themselves to a lack of correspondence between the locking rack and the escapement rack.
12. In a typewriter calculating machine, 20 the combination of a typewriter carriage, a set of numeral keys, an escapement mechanism including an escapement rack and adapted to be governed by any of said numeral keys, a totalizer traveling synchronously with said typewriter carriage, a master wheel mounted in the framework of the machine and adapted to insert numbers in said totalizer upon the actuation of any of 25 said numeral keys, a locking rack moving with said typewriter carriage, a locking dog adapted to enter the teeth of said rack during the insertion of a number, said master wheel and said locking dog being provided 30 with slight lateral motion in the framework, and connections between said locking dog and said master wheel whereby the lateral motion of one will produce a corresponding lateral motion of the other.
13. In a calculating machine, the combination of a master wheel, a shaft upon which 35 said wheel is mounted, said shaft being both rotatably and slidably mounted in the framework of a machine, a locking dog also 40 rotatably and slidably mounted in the framework of a machine, and means connecting said master wheel and locking dog whereby the lateral motion of one will produce lateral motion of the other.
14. In a calculating machine, the combination of a locking dog slidably and rotatably mounted in the framework, a master wheel also slidably and rotatably mounted in the framework, and a connection between 45 said locking dog and said master wheel such that lateral motion of the one will produce lateral motion of the other.
15. In a calculating machine, the combination of a traveling rack, a locking dog

adapted to enter said rack, said locking dog 65 being rotatably and slidably mounted in the framework of a machine, a master wheel mounted rotatably and slidably in the framework of the machine, and a connection between said master wheel and said locking 70 dog to the end that said master wheel and said locking dog will both take a position as determined by the engagement of said locking dog with the teeth of said rack.

16. In a calculating machine, the combination of a decimal carriage, a totalizer mounted on said decimal carriage, a locking rack mounted on said decimal carriage, a locking dog adapted to engage said rack, a master wheel adapted to insert numbers in 80 said totalizer, and connections between said locking dog and said master wheel such that said locking dog and master wheel will assume a position relative to said totalizer as determined by the engagement of said locking dog with said locking rack.

17. In a calculating machine, the combination of a traveling totalizer, a locking rack traveling with said totalizer, a locking dog slidably and rotatably mounted in the framework of the machine and also adapted to engage said totalizer, a master wheel adapted to insert numbers in said totalizer, a set of numeral keys, connections between said numeral keys and said locking dog, a master wheel whereby actuation of any of said keys will first engage said locking dog with said rack and then rotate said master wheel a differential amount, said master wheel and locking dog being so connected that said master wheel and locking dog will both take a position determined by the engagement of said locking dog with said locking rack.

18. In a typewriter calculating machine, 105 the combination of an escapement rack, a locking rack and a floating dog adapted to engage said locking rack.

19. In a typewriter calculating machine, 110 the combination of an escapement rack, a locking rack, a totalizer whose position is determined by the position of said locking rack, a floating dog adapted to engage said locking rack, a floating master wheel and a connection between said dog and said master wheel whereby both dog and master wheel will take a position determined by the contact of said locking dog with said locking rack.

20. In a typewriter calculating machine, 120 the combination of a spring-actuated carriage, an escapement rack controlling the position of said carriage, a locking rack moving with said carriage, and a floating dog adapted to engage said locking rack.

21. In a typewriter calculating machine, 125 the combination of a spring-actuated carriage, an escapement rack controlling the

position of said carriage, a locking rack connected to said carriage, a totalizer also connected to said carriage, a locking dog slidably mounted in the framework and 5 adapted to engage said locking rack, a master wheel slidably mounted in the framework and adapted to engage said totalizer, and means connecting said master wheel and locking dog to locate both of them in a position determined by the engagement of said locking dog with said locking rack.

Signed at Chicago, Illinois, this 5th day of May, A. D. 1917.

ARTHUR F. POOLE.
